**APPARATUS FOR STORING AND WINDING
DISCONTINUOUSLY AND REVERSIBLY MOVING TAPE**

This invention is concerned with the storage and winding of tape adapted to travel, past a reading unit or a working station, in an intermittent or discontinuous manner and adapted to have its direction of travel reversed instantaneously.

Although a length of tape can, because of its low inertia, stand abrupt accelerations and decelerations, in particular instantaneous reversals of its direction of travel, the same does not apply to the tape storage members, i.e. spools, which have an inertia that is dependent on the extent to which they are filled and whose speed cannot abruptly be modified nor, with even greater reason, be instantaneously reversed.

Such a problem may for instance occur when designing magnetic tape sound reproduction apparatus, motion picture projection or filming apparatus and programme reading apparatus for controlling various machines, or with certain tape readers used in computer peripheral equipment.

It has already been proposed, in particular in connection with motion picture apparatus, to provide a loop of film between each of the film spools and the film reading unit, i.e. in the region of the illumination path and the film engaging sprocket teeth.

Although this idea does in fact enable continuous winding on or off of tape to be reconciled with discontinuous travel thereof within a reading unit, it does not however enable the direction of movement of the tape to be reversed instantaneously when its speed of travel has become substantial.

An increase in the size of the tape loops might therefore be thought to be an appropriate idea but this would mean having to provide special means for their storage while in motion.

An object of the present invention is to avoid such a requirement.

According to the present invention there is provided apparatus for storing and winding discontinuously and reversibly moving tape, comprising a pair of holders for supporting a pair of tape spools; a pair of reversible motors for reversibly driving said holders whereby said spools may be alternately receiving and delivering; tape reading means in the path of said tape between said spools; drive means for driving said tape as it enters and as it issues from the reading means; a tape takeup system in the path of said tape for temporarily modifying the length of first and second portions of said path between said drive means and said spools; first supply means actuated by said system and adapted to supply, for each of the spools, a first electric index voltage dependent of the length of the corresponding one of said tape path portions; second supply means associated with each of said spool holders and adapted to supply, for each of the spools, a second electric index voltage dependent on the radius of the last turn of tape wound on the corresponding spool; and electronic circuit means having a comparing element for each spool and adapted to tie the speeds at which said motors drive said spool holders to the corresponding ones of said first and second index voltages; the arrangement being such that under continuous-duty operating conditions of the apparatus, the tape can unwind off the delivering spool and can be wound on the receiving spool at a linear speed equal to that at which it is driven by said drive means, with said first index voltage remaining constant and said second reference voltage, which is variable, progressively modifying the angular speed of the spool associated therewith, and such that any modification in the length of the tape along said path portions causes the takeup system to come into operation and a corresponding variation of the first index voltage to occur which triggers off transitional operating conditions tending to restore said tape path portions to their previous length under continuous-duty operating conditions.

In the accompanying diagrammatic drawings:

FIG. 1 is a front elevation of one form of embodiment of the apparatus provided by the invention;

FIG. 2 is a side elevation of the apparatus shown in FIG. 1, on a larger scale;

FIG. 3 is an axial section, along line III-III of FIG. 4 and to a larger scale, of part of the apparatus shown in FIGS. 1 and 2;

FIG. 4 is a section taken along line IV-IV of FIG. 3;

FIG. 5 is an explanatory graph illustrating the operation of the apparatus shown in FIG. 1 and 2; and

FIG. 6 is a diagram of an electronic circuit used in the apparatus shown in FIGS. 1 and 2.

The apparatus shown in FIG. 1 comprises a baseplate 1 on the front side of which are mounted two delivery cum receiving spools 2 and 3 carried and driven by rotary supports 21 and 31 and containing a tape 4; a drum 5, having a rotary shaft 51, for driving the tape intermediate the two spools; two sets 6 and 7 of pulley arrangements lying in the path of the tape, each between one of the spools 2 and 3 and the driving drum 5; two feelers 8 and 9 pivotally mounted on pins 81 and 91 and carrying at their free ends follower rollers which come to bear under the action of springs 10 and 11 against the outermost turn of tape that is wound on the associated spools. The two sets of pulley arrangements are made up of four rollers 61, 62, 63 and 64, and of four rollers 71, 72, 73 and 74, respectively, that are mounted for free pivotal movement on the baseplate and of three rollers 65, 66 and 67, and of three rollers 75, 76 and 77, respectively, that are mounted for free pivotal movement also on arms 12 and 13. In each of these sets, the tape 4 alternately passes over one of the rollers that are pivotally mounted on the baseplate and over one of the rollers that are pivotally mounted on an arm. Arms 12 and 13 are mounted on pivot pins 121 and 131 and are subjected to the action of tension springs 14 and 15 having one end secured to the arms and having the other end secured to the baseplate 1.

In the illustrated form of embodiment of the apparatus, which is adapted to read information for the control of a machine, in particular a knitting machine, the baseplate 1 carries a unit 17 for reading the information recorded on the tape 4.

On the reverse side of the baseplate are mounted, as shown by FIG. 2, a motor 18 for driving the drum 5; potentiometers 19 and 20 having control pins that are common with the pins 81 and 91 of feelers 8 and 9; potentiometers 22 and 23 having control pins that are common with the pins 121 and 131 of arms 12 and 13; motors 24 and 25, each fitted with reduction gearing, for driving spools 2 and 3; and a drive unit 26 for moving the tape through the reading unit 17.

The supply terminals of motors 24 and 25, of motor 18, of drive unit 26, and of potentiometers 19, 20, 22 and 23, are connected by leads, not shown, to connectors 100 that are mounted on a bus bar 101 secured to the back of the baseplate 1. Other leads, not shown, connect some of the connectors 100 to the electronic circuit shown in FIG. 6.

This electronic circuit which is transistorized, can be mounted on a support that can either be secured to the base plate 1 or be separate therefrom.

Upon issuing from one of the spools 2 and 3 (the delivery spool), the tape 4 is fed to the drum 5 via the corresponding set of pulley arrangements. It then cooperates with the drum a first time and then proceeds along a loop-shaped path towards the reading unit 17 through which it passes. Upon issuing from this reading unit, the tape proceeds back to the drum along a path that is also loop-shaped. The tape then again cooperates with the drum 5, whereupon it proceeds, via the other set of pulley arrangements, towards the other, receiving, spool on which it is wound.

The angular position of the feelers 8 and 9 depends on the amount of tape the spools 2 and 3 carry. The drum 5 is provided with sprocket teeth 51' (FIG. 3) for engagement with perforations formed along the edges of the tape 4 to drive the latter. The same applies to a rotary member, not shown, provided in the reading unit 17 to drive the tape therethrough. The latter is thus driven by both the drum and by this rotary member in the reading unit so that the mean linear speeds at which the drum and this rotary member are driven must be the same.

This condition is here satisfied by fitting the drum 5 and the reading unit 17 with electric synchronous motors, e.g. stepping motors. This requirement for synchronism could also be satisfied by resorting to two motors having controlled

speeds of rotation. This however would involve the use of a servocircuit, thereby rendering the construction of the apparatus substantially more complicated.

As shown in FIG. 3, the drum 5 is mechanically connected to the shaft 181 of motor 18 via a rubber coupling element 182 having four limbs 182a, 182b, 182c and 182d arranged in quadrature formation and giving this element the appearance of a Maltese cross, as can be seen from FIG. 4. The ends of the pair of opposite limbs 182a and 182b are connected to the ends of a diametral element 183, keyed to the motor shaft 181, by connection elements 184. The ends of the pair of opposite limbs 182c and 182d are similarly connected to the rear part of the drum 5 by connection elements 185.

The coupling element 182 is so cut out that each of its limbs may, by elastic deformation, move away from its mean position by + or - 45°. One of the extreme positions the limbs 182c and 182d can occupy is shown in dashed lines in FIG. 4. By virtue of this coupling element, the intermittent motion of the drive shaft 181 is transmitted to the drum 5 as a continuous rotary motion when the drum is driving tape 4.

The motor 18 is fitted with an instantaneous blocking device 186 which comprises a rotary metal disc 187 carried by the opposite end of shaft 181 and coaxial therewith and an electromagnet 188 for axially actuating a nonrotary rubber-lined disc 189 which, upon the electromagnet ceasing to be energized, is applied by spring means, not shown, against the disc 187 to block rotation thereof. This blocking device is meant to be actuated only when the apparatus is being stopped and started.

The electronic circuit shown in FIG. 6 is provided twice, the first time in association with the group consisting of the motor 24 and the potentiometers 19 and 22, and the second time in association with the group consisting of the motor 25 and the potentiometers 20 and 23, with the portion which is surrounded by a dashed line being common to both of these two circuits, and only one of these circuits will now be described.

The energization circuit for the motor 24 or 25 driving spool 2 or 3 is connected to terminals A₁ and A₂ provided in a diode bridge D₁, D₂, D₃, D₄. These terminals A₁ and A₂ are connected one to terminals J₁ and J'₁, the other to terminals J₂ and J'₂ of a reversing switch J having input terminals J₃ and J'₃ which can selectively be connected to the terminals J₁ and J'₂ or J₂ and J'₁, depending on the direction in which the motor is required to rotate.

The linear potentiometer 22 or 23 has extreme terminals B₁ and B₂ which are connected one to terminals K₁ and K'₁, the other to terminals K₂ and K'₂ of a reversing switch K having input terminals K₃ and K'₃ which can selectively be connected to the terminals K₁ and K'₂ or K₂ and K'₁, depending on the direction in which motor 24 or 25 is required to rotate. The potentiometer also has extreme, equipotential, zones B₄ and B₅.

The actuation of the reversing switch J and that of the reversing switch K are coupled and are effected simultaneously by an electromagnet, not shown, which is energized upon reversal of the direction of movement of the tape.

The voltage v₂₂ or v₂₃ that is picked off by the slide B₃ of potentiometer 22 or 23 is dependent on the angular position α of arm 12 or β of arm 13, that is common with the control pin of the potentiometer, and on the direction of movement of the tape. This direction of movement is determined, under continuous-duty operating conditions of the apparatus, by the sign of the angular speed ω of drum 5, which is arbitrarily chosen to be positive when the drum rotates in the direction of arrow F (FIG. 1). The angles α and β are reckoned to be positive in the direction of arrows F₁ and F₂ from the leftmost position of arms 12 and 13 in FIG. 1.

Voltages v₂₂ and v₂₃ respectively vary between 0 and maximum values V₂₂ and V₂₃ which are maintained up to angular positions α_1 and β_1 of arms 12 and 13 when $\omega > 0$, or which are reached at angular positions α_2 and β_2 of arms 12 and 13 when $\omega < 0$, and maintained, in this event, up to the maximum angular positions α_{max} and β_{max} of arms 12 and 13.

FIG. 5 shows, in full lines when $\omega > 0$ and in dashed lines when $\omega < 0$, the variation of voltages v₂₂ and v₂₃ as functions of α and β , respectively.

In FIG. 6, the extreme zones B₄ and B₅ of the resistive element of potentiometer 22 or 23 are occupied by the slide B₃ when $0 < \alpha < \alpha_1$ or $0 < \beta < \beta_1$ and $\alpha_2 < \alpha < \alpha_{max}$ or $\beta_2 < \beta < \beta_{max}$, respectively.

Angles α_1 and β_1 determine the position of terminal B₁ and angles α_2 and β_2 determine that of terminal B₂ on this resistive element.

Potentiometer 19 or 20 is subjected, between its extreme terminals, to a voltage V₁₉ or V₂₀ having a variable fraction v₁₉ or v₂₀ which is picked off by the potentiometer slide C and which is applied, via a diode D₅, to the input terminal K'₃ of the reversing switch K.

The position of the slide C, and hence the value of voltage v₁₉ or v₂₀, is determined by the angular position of the feeler 8 or 9, which angular position depends on the extent to which spool 2 or 3 is filled, this being characterized by the radius r₂ or r₃ of the last turn of tape wound on the corresponding spool.

Since the apparatus being described is meant to control a machine, e.g. a knitting machine, this machine supplies, for instance, through the intermediary of a tachymetric generator not shown, a voltage U which is proportional to its linear speed V_m to which the present apparatus has to adjust its rate of operation.

This voltage U=K₀ V_m is applied to the input of that portion of the transistorized circuit which is surrounded by a dashed line in FIG. 6. This circuit portion delivers, through the intermediary of an input potentiometer P, voltage V₁₉ or V₂₀, these two voltage being identical, so that there is obtained the following relationship:

$$V_{19} = V_{20} = KU$$

and the following consequential relationships:

$$v_{19} = (V_{19}, r_2) = f(KU, r_2)$$

and

$$v_{20} = (V_{20}, r_3) = f(KU, r_3).$$

A fixed, reference, voltage U₀, e.g. of +12 volts or so, is applied to said circuit portion and to the series-mounted resistors R₁ and R₂. A constant fraction

$$\frac{R_2}{R_1 + R_2} U_0$$

of this voltage is applied, via a diode D₆, to the input terminal K'₃ of the reversing switch, which terminal is at the previously mentioned potential V₂₂ or V₂₃.

The circuit (R₁, R₂, D₆) serves to maintain voltages V₂₂ and V₂₃ at least equal to

$$\frac{R_2}{R_1 + R_2} U_0$$

thereby to maintain, at the low values of V_m and hence of U and in particular when the machine is at a stop, the apparatus under servocontrol, and in particular to keep the arms 12 and 13 in their correct positions.

Two cases may arise:

$$60 (a) \quad v_{19} \text{ (or } v_{20}) < \frac{R_2}{R_1 + R_2} U_0$$

so that, via circuit (R₁, R₂, D₆):

$$V_{22} = \frac{R_2}{R_1 + R_2} U_0 \text{ or } V_{23} = \frac{R_2}{R_1 + R_2} U_0$$

$$(b) \quad v_{19} \text{ (or } v_{20}) > \frac{R_2}{R_1 + R_2} U_0$$

so that, via circuit (C, D₅):

$$V_{22} = v_{19} \text{ or } V_{23} = v_{20}$$

Potentiometer 22 (or 23) being linear, the following relationships moreover occur (FIG. 5):

if $\omega > 0$:

$$\begin{aligned} 0 \leq \alpha \leq \alpha_1 & \quad v_{22} = V_{22} \\ \alpha_1 < \alpha < \alpha_2 & \quad v_{22} = \frac{\alpha_2 - \alpha}{\alpha_2 - \alpha_1} V_{22} \\ \alpha_2 \leq \alpha \leq \alpha_{\max} & \quad v_{22} = 0 \end{aligned}$$

OR:

$$\begin{aligned} 0 \leq \beta \leq \beta_1 & \quad v_{23} = V_{23} \\ \beta_1 < \beta < \beta_2 & \quad v_{23} = \frac{\beta_2 - \beta}{\beta_2 - \beta_1} V_{23} \\ \beta_2 \leq \beta \leq \beta_{\max} & \quad v_{23} = 0 \end{aligned}$$

if $\omega < 0$:

$$\begin{aligned} 0 \leq \alpha \leq \alpha_1 & \quad v_{22} = 0 \\ \alpha_1 < \alpha < \alpha_2 & \quad v_{22} = \frac{\alpha - \alpha_1}{\alpha_2 - \alpha_1} V_{22} \\ \alpha_2 \leq \alpha \leq \alpha_{\max} & \quad v_{22} = V_{22} \end{aligned}$$

OR:

$$\begin{aligned} 0 \leq \beta \leq \beta_1 & \quad v_{23} = 0 \\ \beta_1 < \beta < \beta_2 & \quad v_{23} = \frac{\beta - \beta_1}{\beta_2 - \beta_1} V_{23} \\ \beta_2 \leq \beta \leq \beta_{\max} & \quad v_{23} = V_{23} \end{aligned}$$

Voltage V_{22} or V_{23} is applied to a load resistor R_3 .

A resistor R_4 , placed at the output of the slide B_3 of potentiometer 22 or 23, and a resistor R_5 , placed at the output of the slide C of potentiometer 19 or 20, enable the power level to be adapted at point Q and are loaded by a resistor R_6 . The voltage V_q at point Q is of the form:

$$V_q = k_1 v_{19} + k_2 v_{22} \text{ or } k_1 v_{20} + k_2 v_{23}$$

This potential thus depends linearly of the value of voltages v_{19} and v_{22} or of the value of voltages v_{20} and v_{23} , i.e. of the angular positions of feeler 8 and of arm 12 or of feeler 9 and of arm 13, in other words of the parameters r_2 and α or r_3 and β , respectively. Any variation of these parameters brings about a proportional variation of the voltage V_q , termed "index" voltage.

A servocircuit is provided so as permanently to regulate the energization of motor 24 or 25 in dependence on the value of parameters r_2 and α or r_3 and β , respectively, i.e. to subject the speed of the motor to these parameters.

This servocircuit comprises a comparator cum amplifier CA having a feedback line (resistor R_7 , capacitor C_3) by means of which the gain can be increased.

Comparator cum amplifier CA has two inputs E_1 and E_2 . To the first, E_1 , is applied the index voltage V_q ; to the second, E_2 , is applied a voltage V_s from point S and termed "measurement" voltage, which is proportional to the energizing power of motor 24 or 25 and which is derived from this power, off terminal J_3 of the reversing switch J, via a resistor R_8 loaded by a resistor R_9 .

Comparator cum amplifier CA serves to reverse one of its input voltages, V_q , then to add it to the other, V_s , and to amplify the quantity $V_s - V_q$ thereby to supply, at its output E_3 , an error signal e having a sign which is the same as that of $V_s - V_q$. The resistance values of resistors R_4 , R_5 , R_6 , R_8 and R_9 are so chosen that under continuous-duty operating conditions of the apparatus, this error signal may be nil or remain less than a threshold value at which the servoaction is triggered off, i.e. that V_q may be substantially equal to V_s .

The servocircuit comprises, moreover, a current source which includes resistors R_{10} , R_{11} , R_{12} , a transistor T_1 and a Zener diode Z, and which delivers a constant current I_2 of which one fraction i_1 is regulated by a transistor T_2 (whose base is connected to its emitter by a capacitor C_2) in dependence on the error signal e which is applied to its base via a resistor R_{13} , and of which the other fraction $i_2 = I_2 - i_1$ is forwarded to a power amplifier forming the final portion of the servocircuit.

This amplifier, which comprises resistors R_{14} , R_{15} , R_{16} , R_{17} and R_{18} , transistors T_3 , T_4 , T_5 and T_6 , diodes D_7 and D_8 , and a chemical capacitor C_1 , delivers to the terminal J_3 of reversing switch J the energizing power for motor 24 or 25.

The circuit includes a portion which consists of diodes D_9 and D_{10} , transistors T_7 and T_8 , resistors R_{19} , R_{20} , R_{21} and R_{22} , and which enables the current discharged by the motor 24 or 25 to be absorbed and to be limited when the latter, upon reversal of its energization by actuation of the reversing switch J, operates, through inertia, as a generator before stopping and reversing its direction of rotation. Current sources P_1 , P_2 and P_3 discharge at constant voltages V_1 , V_2 and V_3 , respectively.

The following table shows the values that are given to the various resistors in the circuit represented in FIG. 6:

Resistor:	Value in KΩ	Resistor:	Value in KΩ
R_1	10	R_{12}	0.39
R_2	0.56	R_{13}	2.2
R_3	2	R_{14}	0.1
R_4	4.7	R_{15}	0.1
R_5	12	R_{16}	0.27
R_6	10	R_{17}	1
R_7	75	R_{18}	1
R_8	20	R_{19}	0.47
R_9	5.15	R_{20}	1
R_{10}	2.7	R_{21}	1.2
R_{11}	1.2	R_{22}	1

When the above described apparatus is operating under continuous-duty operating conditions, the direction of travel of the tape 4 is defined, as has been seen, by the sign of the angular speed ϵ of drum 5, this sign being chosen positive in the direction of arrow F.

Under transitional operating conditions, this sign only defines the direction of travel of the tape in the drum 5 and the reading unit 17.

The speed of the motor controlling the rotary member that drives the tape in the reading unit 17 and the speed of the motor driving drum 5 are adjusted to the speed of operation, V_m , of the machine to which the apparatus is fitted. These two motors can, to this end, be driven by impulses emitted by the machine and having a frequency proportional to V_m . As will be seen further on, the operation of the drum motor remains, however, dependent on that of the motor controlling the rotary member in the reading unit.

A. CONTINUOUS-DUTY OPERATING CONDITIONS

Under continuous-duty operating conditions, the mean linear speed of the tape 4 is uniform and is the same over its entire path of travel, i.e. from when it is unwound off the delivery spool (3 if $\omega > 0$)

2 if $\omega < 0$ until it is rewound on the receiving spool (2 if $\omega > 0$)
3 if $\omega < 0$.

The linear speed of the tape on the drum is made uniform, despite the jerky motion of the drum motor, by means of the transmission arrangement described above with reference to FIGS. 3 and 4.

The motion of the tape through the reading unit 17 remains jerky but the mean linear speed of the tape is the same as the even speed over the drum 5.

In this form of embodiment, wherein the motors for the reading unit 17 and the drum 5 are stepping motors, a counting circuit, not shown, is provided to trigger off, outside the periods in which the direction of travel of the tape is reversed, one step of the drum motor for every three steps of the reading unit motor, the angular amplitude of the steps of these two motors being of course dependent on the diameter of the drum and on the diameter of the tape driving member in the reading unit so that the linear speed of the tape may, on average, be the same over the drum and in the reading unit.

The arms 12 and 13 remain in a substantially mean angular position: $\alpha_m = \frac{1}{2}(\alpha_1 + \alpha_2)$ and $\beta_m = \frac{1}{2}(\beta_1 + \beta_2)$, respectively, shown in full lines in FIGS. 1. The slide B₃ of potentiometer 22 or 23 remains in the corresponding mean position it occupies in FIG. 6.

As the tape leaves the delivery spool to be wound on the receiving spool, the angular position of the feelers 8 and 9 changes in inversely proportional manner to r_2 and r_3 , respectively. This results in a corresponding displacement of the slide C of potentiometers 19 and 20, respectively.

If $\omega > 0$:

The spool 2 is receiving: r_2 is increasing and v_{19} is decreasing.

As long as

$$v_{19} > \frac{R_2}{R_1 + R_2} U_0, v_{19} = V_{22}$$

which decreases and causes a decrease of

$$v_{22} = \frac{\alpha_2 - \alpha}{\alpha_2 - \alpha_1} V_{22} \left(\alpha_1 < \alpha = \alpha_m \sim \frac{\alpha_1 + \alpha_2}{2} < \alpha \right)$$

and a decrease of $V_q = k_1 v_{19} + k_2 v_{22}$.

The comparator cum amplifier CA of the electronic circuit that is associated with the potentiometers 19 and 22 and with the motor 24, delivers an error signal $\epsilon > 0$ proportional to $V_s V_{qav} > 0$ which, by acting on the base of the transistor T₂, causes the current i_1 to increase and hence brings about a decrease of the current i_2 and, via the circuit for amplifying the power for the energization of motor 24, a slow down of this motor. The voltage V_s is thus reduced and again compared to the decreasing voltage V_q . The quantity $V_s - V_q$, which is still positive, continues to cause the motor 24 to slow down.

Spool 3 is delivering: r_3 is decreasing and v_{20} is increasing.

As long as

$$v_{20} > \frac{R_2}{R_1 + R_2} U_0, v_{20} = V_{23}$$

which increases and causes an increase of

$$v_{23} = \frac{\beta - \beta_1}{\beta_2 - \beta_1} V_{23} \left(\beta_1 < \beta = \beta_m \sim \frac{\beta_1 + \beta_2}{2} < \beta_2 \right)$$

and an increase of $V_q = k_1 v_{20} + k_2 v_{23}$.

The comparator cum amplifier CA of the circuit that is associated with the potentiometer 20 and 23 and with the motor 25, delivers an error signal $\epsilon < 0$ proportional to $V_s - V_{q0} < 0$ which, by acting on the base of the transistor T₂, causes the current i_1 to decrease and hence brings about an increase of the current i_2 and, via the circuit for amplifying the power for the energization of motor 25, an acceleration of this motor. The voltage V_s is thus increased and again compared with the decreasing voltage V_q . The quantity $V_s - V_q$, which is still negative, continues to cause the motor 25 to accelerate.

If $\omega < 0$:

Spool 2 is delivering and r_2 is decreasing. The circuit which is associated with the potentiometers 19 and 22 and with the motor 24 reacts to this decrease of r_2 in the same way as the circuit which is associated with the potentiometers 20 and 23 and with the motor 25 when $\omega > 0$, and so causes the motor 24 to accelerate.

Spool 3 is receiving and r_3 is increasing. The circuit which is associated with the potentiometers 20 and 23 and with the motor 25 reacts to this increase of r_3 in the same way as the circuit which is associated with the potentiometers 19 and 22 and with the motor 24 when $\omega > 0$, and so causes the motor 25 to slow down.

Of course, this subjection of the operating conditions of motors 24 and 25 to the values of parameters r_2 and r_3 , respectively, is carried out instantaneously and continuously.

B. TRANSITIONAL OPERATING CONDITIONS

Transitional operating conditions come into being in the operation of the present apparatus whenever there occurs a

variation in the speed V_m that characterizes the operating conditions, or the working rate, of the machine with which the present apparatus is associated, or a variation in the angular speed of the spools 2 or 3 in relation to the value this speed has under continuous-duty operating conditions, or else a change in the value or of the sign of ω .

These various factors bring about a momentary break in the synchronism existing between the operation of the spools 2 and 3 and that of the members which cooperate with the tape 4 along its path of travel, i.e. the drum 5 and the reading unit 17. This gives rise to a change in the length of this path of travel, which change is absorbed by the arms 12 and 13, under the action of the springs 14 and 15, by modifying their angular positions (angles α and β).

a. Variation of V_m

It may happen, for instance as a result of a variation in the frequency of the mains supplying the machine, or of a desired change in the working rate of the machine, that the linear speed V_m comes to be modified. It is imperative that the apparatus should adjust as quickly as possible to this new working rate set by the machine.

If $\omega > 0$, spool 2 is receiving and spool 3 is delivering. A reduction of V_m immediately causes a corresponding decrease in the speed at which the tape is driven in the reading unit 17 and a corresponding decrease of ω , whereas spools 2 and 3 do not instantaneously change their rate of motion.

This gives rise to an increase in the length of tape between the spool 3 and the drum 5, which increase is absorbed by an increase in β on account of the compensating action of the spring 15 on arm 13, and further gives rise to a corresponding decrease in the length of tape between the drum 5 and the spool 2, which decrease is absorbed by an increase in α , the arm 12 tensioning the spring 14.

This decrease in V_m causes a decrease in the voltage U which in turn causes a drop in V_{19} and V_{20} and hence a drop in V_{22} and V_{23} , respectively.

The increase of α and of β (FIG. 5) causes a decrease in v_{22} and in v_{23} , this decrease being accentuated by the drops in V_{22} and in V_{23} . This gives rise to a decrease in V_q and, since $V_s - V_q$ becomes > 0 , to the emission by the comparator cum amplifier CA of an error signal $\epsilon > 0$ which causes i_1 to become larger and i_2 to become smaller, thus reducing the energization of the motors 24 and 25 driving spools 2 and 3, which motors slow down and cause α and β to become smaller thereby progressively to return them to their continuous-duty operating conditions value.

Similarly, an increase in V_m brings into being transitional operating conditions starting off with a decrease in the length of tape between the spool 3 and the drum 5, which decrease is absorbed by a decrease in β that tensions spring 15, and with an increase in the length of tape between the drum 5 and the spool 2, which increase is absorbed by a decrease in α on account of the compensating action of the spring 14 on arm 12. These transitional operating conditions result in an increase in the angular speed of spools 2 and 3.

What has just been explained in relation to $\omega > 0$ can be transposed without difficulty to the case where $\omega < 0$ with the spool 2 delivering and the spool 3 receiving.

b. Variation in the speed of the spools 2 and 3 in relation to their continuous-duty operating conditions speed:

It may happen that the angular speed of one of the spools 2 and 3, or both simultaneously, be subjected to an abrupt change. Let it be assumed, for instance, that the receiving spool 2 comes to slow down ($\omega > 0$): the length of tape between this spool and the drum 5 increases and this increase in length is absorbed, under the action of spring 14, by a displacement of arm 12 which decreases angle α . FIG. 5 shows that this decrease of α causes v_{22} to increase and hence, all other things being equal, an increase of V_q and the appearance of a difference $V_s - V_{q0}$ causing the comparator cum amplifier CA to emit an error signal $\epsilon < 0$ which causes i_1 to become smaller and hence i_2 to become larger. This larger i_2 causes the energization of motor 24 to increase thereby accelerating

spool 2 and reducing the excess length of tape between the spool and the drum 5, thus causing an increase of α which, progressively and at the same time as the angular speed of this spool, returns to its continuous-duty operating conditions value.

Any other variation of the speed of spools 2 and 3 when $\omega > 0$ causes in like manner the appearance of transitional operating conditions which restore the angular speed of these spools to their continuous-duty operating conditions value.

c. Variation of ω :

An abrupt variation in the value of ω triggers off transitional operating conditions of the kind described under a, except that since V_m is constant, voltages V_{22} and V_{23} do not vary.

d. Reversal of the sign of ω :

The tape 4 is alternately read in one direction of travel and then in the other ($\omega > 0$ and $\omega < 0$). The reversal of this direction of movement is triggered off by the reading of a reversal item of information carried by the tape and occurs instantaneously in the reading unit. This reversal causes, through the intermediary of an electromagnet not shown, the reversing switches J and K to change over.

In order to give the drum 5, now being driven by inertia, time to stop, the previously mentioned counting circuit triggers off the first reversed step of the drum motor only after the reading unit motor has moved, in its new direction of rotation ($3n+x$) steps, x being the number of steps made by this motor in its previous direction of rotation between the time the last drum motor step was triggered off and the time when the reversal item of information was read. The number n may be equal to 3, 4 or even 5. This results, on opposite sides of the reading unit, in a dissymmetry of the loop formed by the tape due to the time lag between the reversal of the sign of ω after the reversal of the direction of movement of the tape in the reading unit. This dissymmetry subsists as it is until the next reversal of the sign of ω .

The changing over of the reversing switch J causes the value of v_{22} , as a function of α , or of v_{23} , as a function of β , to pass from one curve of FIG. 5 to the other, whereas the changing over of the reversing switch K reverses the energization of motors 24 and 25.

The inertia of spools 2 and 3, which becomes quite substantial by virtue of the amount of tape wound thereon, does not enable the direction of rotation of the spools to be instantaneously reversed. Transitional operating conditions thus come into being upon reversal of the sign of ω .

Although the energization of the motors 24 and 25 is instantaneously reversed, the latter still retain for a certain length of time, termed kinematic reversal time, the same direction of rotation, through being driven by the inertia of the spools 2 and 3.

This kinematic reversal time may amount to a few tenths of a second in the case of a linear tape travel speed of about 100 cm/sec. It depends, in the case of each spool, on the extent to which it is filled.

Supposing, for instance, that ω is initially positive, with spool 2 receiving and spool 3 delivering, the tape 4 continues, during this kinematic reversal time, to be wound by spool 2 and to be unwound by spool 3 when it is in fact already being driven in the opposite direction by the drum 5 and in the reading unit 17, ω having become negative. This results in a decrease in the length of tape between the spool 2 and the drum 5 and in an increase in the length of tape between the drum 5 and the spool 3, which decrease and which increase are respectively absorbed by an abrupt increase of α and β .

Upon being so driven, both motors 24 and 25 operate as generators and the current they supply is looped through earth via the diode bridge (D₁, D₂, D₃, D₄) and the transistor T₇, which becomes unblocked as soon as the value of the voltage at the terminals of resistor R₂₁ exceeds a threshold value. This current exerts a braking action on the motor which slows down. The voltage at the terminals of resistor R₂₁ decreases and because this current is now decreasing as a result of the motor slowing down, the transistor T₇ becomes blocked as

soon as the voltage at the terminals of resistor R₂₁ has dropped back below said threshold value. The motors 24 and 25 then stop whereupon they reverse their direction of rotation and gather up speed while causing α and β to decrease.

- 5 ω being negative, the variation of $v_{22}=f(\alpha)$ and of $v_{23}=f(\beta)$ is represented by the curve shown in dotted lines in FIG. 5. The effect of decreasing α and β is to cause v_{22} and v_{23} , and hence V_a , to rise and to cause a difference $V_s - V_0$ to appear which generates at the output of the comparator cum amplifier an error signal $\epsilon > 0$ that increases i_1 , and that decreases i_2 and hence the energization of motor 24 or 25, the apparatus as a whole tending progressively to achieve new continuous-duty operating conditions characterized by $\alpha \sim \alpha_m$ and $\beta \sim \beta_m$.

Of course, transitional operating conditions similar to those which have just been described will come into being when ω again becomes positive upon the direction of travel of the tape being again reversed.

We claim:

1. Apparatus for storing and winding a discontinuously and reversibly moving tape, comprising a pair of holders for supporting a pair of tape spools; a pair of reversible motors for reversibly driving said holders whereby said spools may be alternately receiving and delivering; tape reading means in the path of said tape between said spools; drive means for driving said tape as it enters and as it issues from the reading means, a tape takeup system in the path of said tape for temporarily modifying the length of first and second portions of said path between said drive means and said spools; first supply means actuated by said system and adapted to supply, for each of the spools, a first electric index voltage dependent on the length of the corresponding one of said tape path portions; second supply means associated with each of said spool holders and adapted to supply, for each of the spools, a second electric index voltage dependent on the radius of the last turn of tape wound on the corresponding spool; and electronic circuit means having a comparing element for each spool and adapted to tie the speeds at which said motors drive said spool holders to the corresponding ones of said first and second index voltages; the arrangement being such that under continuous-duty operating conditions of the apparatus, the tape can unwind off the delivering spool and can be wound on the receiving spool at a linear speed equal to that at which it is driven by said drive means, with said first index voltage remaining constant and said second reference voltage, which is variable, progressively modifying the angular speed of the spool associated therewith, and such that any modification in the length of the tape along said path portions causes the takeup system to come into operation and a corresponding variation of the first index voltage to occur which triggers off transitional operating conditions tending to restore said tape path portions to their previous length under continuous-duty operating conditions.

2. Apparatus according to claim 1, further comprising a baseplate through which project said holders and on one face of which are mounted said tape reading means, said drive means and said tape takeup system, wherein said takeup system includes first and second arms disposed on opposite sides of said tape reading means and carried by first and second pivot pins mounted in said baseplate for angular movement between first and second extreme positions, first and second sets of pulley arrangements adapted to cooperate with said tape and respectively disposed along said first and second tape path portions, each set having a first plurality of rollers pivotally mounted on a corresponding said arm and a second plurality of rollers pivotally mounted on said baseplate, said tape being arranged to cooperate, during operation, with alternate ones of said first and second pluralities of rollers whereby the angular position occupied by said first and second arms between said extreme positions will determine the length of said first and second tape path portions, respectively, said system further including first and second spring means cooperating with said first and second arms, respectively, and urging said arms into angular positions lengthening the corresponding tape path portions.

3. Apparatus according to claim 2, wherein said first supply means include first and second linear potentiometers actuated by said first and second pivot pins, the supply of each of said potentiometers being reversible at the same time as the direction of travel of the tape.

4. Apparatus according to claim 3, wherein said potentiometers have each two extreme, equipotential, zones which correspond to regions in the angular movement of said arms adjacent said extreme positions.

5. Apparatus according to claim 1, wherein said second supply means include first and second feeler arms which are carried by first and second pivot pins mounted in said baseplate in the vicinity of said spool holders and which carry at their free ends first and second follower rollers for engagement with the last turn of tape wound on said spools, respectively, when mounted on said holders, first and second spring means cooperating with said first and second feeler arms to urge said follower rollers, during operation, into engagement with the last turn of tape wound on said spools, and first and second linear potentiometers controlled by said first and

second pins, the value of said second electric index voltage supplied during operation by said second supply means for each spool being dependent on the angular position of the corresponding one of said feeler arms, said angular position being in turn dependent on the radius of the last turn of tape wound on the corresponding spool.

6. Apparatus according to claim 1, wherein said comparing element for each spool is a comparator cum amplifier having a first input for receiving an index voltage resulting linearly 10 from said first and second electric index voltages, and having a second input for receiving a measurement voltage which is proportional to the power for energizing the corresponding spool-holder driving motor, the difference between the measurement voltage received at said second input and the index 15 voltage received at said first input being amplified by said comparator cum amplifier and giving rise to an error signal, either positive or negative, which reacts on the energization of said corresponding motor and hence on the angular speed of the spool-holder driven by said motor.
